UNITED STATES PATENT OFFICE.

SIMON PETER BILYEU, OF SACRAMENTO, CALIFORNIA.

FLUSHING APPARATUS FOR CLOSETS.

1,184,713.

Specification of Letters Patent. Patented May 30, 1916.

Application filed September 18, 1914. Serial No. 862,396.

To all whom it may concern:

Be it known that I, SIMON PETER BILYEU, a citizen of the United States, residing at Sacramento, in the county of Sacramento 5 and State of California, have invented certain new and useful Improvements in Flushing Apparatus for Closets, of which the following is a specification.

My invention relates to new and useful 10 improvements in flushing apparatus for closets.

The primary object of the invention is the provision of such an apparatus which will be operated from the seat.

15 A further object is the provision of such an apparatus wherein a predetermined amount of water is allowed to flow for the flushing.

With these and other objects in view the 20 invention consists in the novel details of construction and arrangement of parts which will be more clearly understood from the following description and drawings, in which,

25 Figure 1 is a front elevation. Fig. 2 is a side elevation. Fig. 3 is a top plan of the seat. Fig. 4 is a top view of the valve-operating gear, and Fig. 5 is a vertical section through the motor.

30 In the drawings, the numeral 1 indicates a closet bowl of ordinary construction and 2 the seat hinged thereto. The water supply pipe is indicated, at 3, and enters the bowl, at 4. A rotary valve is placed within 35 the pipe 3, as shown at 5, and on the extension 6 thereof is a small gear or pinion 7. A large gear 8 is secured to the pipe 3 by means of a clamp 9 and meshes with a small gear pinion 10 secured to the pipe by means 40 of the clamp 11. Secured to the small pinion 10 is a large gear 12. Intermediate the ends of the pipe 3 is an enlarged casing 13 in which operates a motor or paddle wheel 14 and on the end of the motor-shaft 15 is 45 a small pinion 16 which meshes with the large gear 12 above described.

50 A bell crank arm 17 is loosely mounted on the extension 6 of the valve and carries a pawl 18 which is adapted to engage the teeth of the small gear or pinion 7. A rod 19 is secured to the end of the bell crank lever and extends downwardly to a point below the top of the bowl 1. A rod 20 is 55 pivotally connected to the bowl, at 21, and extends at an angle. One end of the rod is pivotally connected to the rod 19, at 22, and

the opposite end is engaged by a projection or plate 23 carried by the seat. A coil spring 24 is connected at one end to the rod 19 and at the opposite end to the floor, as 60 shown at 25. Secured to the large gear 8 is a gear fragment or segment 26 which is adapted to mesh with the small gear or pinion 7 while closing the valve.

Having fully described the detailed construction of the device it is thought that the operation will be clear.

When the several parts are in the position shown in Figs. 1 and 2 of the drawings, the valve is closed and no water is admitted to 70 the bowl. When the seat 2 is depressed the rod 20 is swung on the pivot point 21 and raises the rod 19 which, through means of the crank arm 17, causes the pawl 18 to pass over the teeth of the pinion 7. When the 75 parts are in this position the spring 24 will be under tension. When pressure is removed from the seat 2 the same will be raised by means of the spring 24 pulling down upon the rod 19 and as this pulls on the crank 80 arm 17 the pawl 18 will engage the teeth of the pinion 7, thereby rotating the same and opening the valve 5. The water passing through the pipe 3 engages the motor or paddle wheel 14, thereby revolving the same 85 and turning the gear 16 which in turn operates the gear 12 which, through means of the small gear 10, rotates the large gear 8. The fragmental gear 26 is disengaged from the pinion 7 upon the first rotation of the 90 large gear 8 so that the large gear 8 rotates one entire revolution without meshing with the pinion 7 or turning the valve. Upon the complete rotation of the gear 8 the fragmental gear 26 will engage the small gear or 95 pinion 7, thereby rotating the same and closing the valve. By this construction it will be seen that only a predetermined amount of water will be used in flushing the closet.

Having fully described my invention what 100 I claim as new and desire to secure by Letters Patent is:

1. The combination with a closet, a seat hinged thereto, an inlet pipe, a valve in said pipe and having a gear secured thereto, a 105 motor mounted in the pipe, a pawl engaging the gear on the valve, a rod connected to the pawl and to the seat, a gear secured to the motor, and a plurality of gears connecting the motor gear and valve gear.

2. The combination with a closet, a seat hinged thereto, a lever pivotally connected 110

to the closet and engaging the seat, an inlet pipe, a valve within said pipe and having a gear secured thereto, a pawl engaging the gear, a rod connecting the pawl and lever 5 pivoted to the closet, a motor mounted in the pipe and having a gear secured thereto, and a plurality of gears connecting the motor gear and valve gear.

3. The combination with a closet, a seat 10 hinged thereto, a lever pivoted to the closet and engaging the seat, an inlet pipe, a valve within said pipe and having a gear secured thereto, a pawl adapted to engage the gear, a rod connecting the pawl and closet lever, 15 a motor within the pipe, a gear secured to the motor, a gear secured to the pipe and connected to the motor gear, and a fragmental gear secured to said gear clamped to the pipe and adapted to engage the valve gear.
- 20 4. The combination with a closet, a seat hinged thereto, a lever pivoted to the closet and engaging the seat, an inlet pipe, a valve within the pipe, a gear secured to the valve, a pawl adapted to engage the valve gear, a 25 rod connected to the pawl and closet lever,

a spring secured to the rod, a motor within the pipe, a gear secured to the motor, a gear clamped to the pipe and connected to the motor gear, and a fragmental gear secured to said gear clamped to the pipe and adapted to mesh with the valve gear. 30

5. The combination with a closet, a seat hinged thereto, a lever pivotally connected to the closet and engaging the seat, an inlet pipe, a valve within said pipe and having a gear secured thereto, a bell crank lever 35 loosely mounted on the gear shaft, a pawl carried by the bell crank lever and adapted to engage the gear, a rod connected to the bell crank lever and to the lever pivoted to the closet, a motor mounted in the pipe and having a gear secured thereto, and a plurality of gears connecting the motor gear and valve gear. 40

In testimony whereof I affix my signature 45 in presence of two witnesses.

SIMON PETER BILYEU.
